RECOVERY OF HYDROGEN FROM
REFINERY GAS

Amilcare Ramella, Woodbury, N.J., assignor to Socony
Mobil Oil Company, Inc., a corporation of New York
Filed May 28, 1962, Ser. No. 197,987
14 Claims. (Cl. 23—212)

The present invention relates to the recovery of hydrogen of high purity, of at least 90% by volume, from industrial gas streams comprising hydrogen and components not reactive with extracting agent and, more particularly, to the recovery of hydrogen from refinery gas streams containing at least 20 percent by volume of hydrogen and comprising hydrogen and hydrocarbons with or without ammonia, hydrogen sulfide and the like.

Reforming of hydrocarbons and particularly petroleum hydrocarbons involves dehydrogenation of naphthene, dehydrogenation of paraffins, dehydrocyclization of paraffins, isomerization of normal paraffins to iso-paraffins, and hydrocracking of paraffins. The greater the severity of reforming conditions the greater the dilution of hydrogen produced in the dehydrogenation of naphthenes and the dehydrocyclization of paraffins with hydrocarbon fragments such as methane, ethane, and propane.

With the increased demand for high octane gasoline, e.g., C₅₊ reformate having an octane rating (Research +3 ml. TEL) of 100 the purity of reformer hydrogen has decreased. Present demands for hydrogen on the other hand have increased.

Thus, for example, it is a matter of economics whether Mid-Continent naphtha be hydrogenated to reduce the sulfur content to provide reformer feed for a reformer unit employing particle-form platinum-group metal reforming catalyst. On the other hand, when thermal naphtha is to be reformed in the presence of platinum-group metal reforming catalyst there is no choice. The nitrogen content of thermal naphtha is so high that the platinum-group metal reforming catalyst is inactivated in an impractically short time when the thermal naphtha is not hydrodesulfurized and hydrodenitrogenized prior to reforming. Consequently, the increased demand for upgrading previously accepted gasolines has required reforming of thermal naphtha and consequently increased demand for hydrogen to hydrodecontaminate the thermal naphtha.

It is now rather general practice to hydrodecontaminate domestic fuel oil and similar hydrocarbon fractions boiling above gasoline to upgrade these fractions thus making a further demand for hydrogen.

The problem of meeting the more stringent specifications for jet fuels is being solved at least in part by hydrogenation of the naphthenes of the jet fuel.

The treatment of lubricating oil fractions in the presence of hydrogen has also been added to the list of refinery operations using hydrogen produced in the reforming unit. In fact, the demand for hydrogen for pretreating reformer feed, hydrodesulfurizing domestic fuel oil, hydrogenerating jet fuel fractions, hydrotreating lubricating fractions, and hydrocracking crudes, deasphalted crudes, topped crudes, and gas oil fractions exceeds the supply with the consequent result that the reformer make-gas is passed from one refinery operation to another provided the contaminants picked up in one operation are not deleterious to the succeeding operation.

Hydrogen can be produced by partial oxidation of hydrocarbons and by other means but not at a cost which makes its use attractive in the aforementioned and other refinery hydroprocesses. On the other hand, there are refinery gas streams containing hydrogen but of such low concentrations that the use thereof is not practical.

For example, the off-gas of catalytic cracking of gas

2

oil such as the off-gas from the Thermofer Catalytic Cracking of gas oil has the following composition:

TABLE I

Constituent of	Mol percent
TCC-off-gas:	
Hydrogen	35.0
Methane	32.0
Ethylene	7.0
Ethane	15.0
Propylene	7.0
Propane	3.0
Butanes	0.9
Hydrogen sulfide	0.1
Total	100.0

In other words, were TCC off-gas to be used in hydroprocessing for every 1000 s.c.f. of hydrogen circulated 2855 s.c.f. of diluent gas must also be compressed and transported. Many of the hydroprocesses can be carried out at lower pressure. That is to say, it is the partial pressure of hydrogen not the total pressure which is controlling in many hydroprocesses. Hence, the higher the purity of the hydrogen-containing gas the lower the total pressure for a given hydrogen partial pressure. The lower the pressure the lower the capital cost; the higher the purity of the hydrogen-containing gas stream the lower the compression costs; the higher the purity of the hydrogen-containing gas the lower the aging rate and the longer the interval between regenerations, i.e., the longer the on-stream time and the fewer the off-stream times for regeneration of the catalyst in a given calendar interval. For example, a decrease of about 20% in investment cost of a new hydrodesulfurization unit treating middle distillate can be realized by employing recovered hydrogen of 90% purity over the use of reformer make-gas of 60% purity. For a hydrodesulfurization unit treating 7,000 barrels of middle distillate per day the saving in investment cost can amount to about \$250,000. On an existing hydrodesulfurization unit employing the recovered hydrogen of 90% purity can double the on-stream time of the unit between regenerations.

Thus, it is manifest that a means of raising the hydrogen content of refinery gas streams will make available hydrogen which cannot be presently used and the availability of 90 percent by volume hydrogen will present additional advantages. The present invention provides the solution to the twin problems.

In general, the present invention provides for contacting any refinery stream containing at least 20 percent by volume of hydrogen with a hydrogenatable extracting agent in the presence of a hydrogenation catalyst under hydrogenating conditions of temperature, pressure, and liquid hourly space velocity to react the hydrogen in the gas stream with the hydrogenatable extracting agent to produce fat extracting agent and off-gas of reduced concentration of hydrogen. The fat extracting agent is separated from the denuded gas stream. The fat extracting agent is then contacted with dehydrogenating catalyst under dehydrogenating conditions of temperature, pressure, and liquid hourly space velocity to produce a gaseous fraction containing at least 90 percent by volume of hydrogen and lean extracting agent. The high purity gas stream flows to other hydroprocesses while the lean extracting agent is returned to the hydrogenation stage.

The method of recovering hydrogen of at least 90 percent purity briefly and generally described hereinbefore is to be distinguished over the method of purifying reformer recycle gas described in U.S. Patent No. 2,328,828 issued in 1943.

The patentee describes a process in which naphtha having an ASTM knock rating of about 25 to 45 mixed with

about 0.5 to 4 mols of hydrogen per mol of said naphtha is contacted with dehydrogenating catalyst such as chromia or molybdena on alumina at pressures of about 50 to 450 p.s.i., 900° to 1025° F. and at liquid hourly space velocities of about 0.1 to 10 to produce a product which is fractionated into a bottoms product boiling higher than gasoline, a heavy naphtha, a benzene fraction boiling in the range of about 160° to 185° F. and uncondensed overhead vapors. The overhead of the fractionation is stabilized at 150 to 500 p.s.i. to produce a side-stream comprising C₃ and C₄ hydrocarbons, a light naphtha which is mixed with the aforesaid heavy naphtha, and a stabilizer overhead containing 25 to 75 percent by volume of hydrogen. The stabilizer overhead in part can be discharged from the system although it is preferred to contact the stabilizer overhead in admixture with the aforesaid benzene fraction with a hydrogenating catalyst at hydrogenating conditions of temperature of about 300° to 800° F. and pressures of about 50 to 5000 p.s.i. The benzene fraction is hydrogenated and separated from the treated stabilizer overhead. The hydrogenated benzene fraction is then contacted in admixture with the feed naphtha or separately with dehydrogenating catalyst at 900° to 1025° F., at 50 to 450 p.s.i., and at liquid hourly space velocities of about 0.1 to 10. The patentee also states that for naphthas having end boiling points below 450° F. diphenyl may be employed and for naphthas having boiling temperatures below 375° to 400° F. naphthalene can be used.

Since in the patented process gasoline is produced in admixture with the produced hydrogen and dehydrogenated benzene or diphenyl or naphthalene the condition of dehydrogenation must be regulated to be the optimum for the production of gasoline of the required octane rating regardless of the conditions which are optimum for recovery of the hydrogen and for minimum degradation of the naphthalene, diphenyl, xylene, toluene, or benzene. Degradation of the aromatic hydrocarbons by dealkylation during dehydrogenation dilutes the hydrogen produced and undoubtedly at least in part accounts for the failure to exploit this process industrially.

In direct contrast to the foregoing method of returning to the reformer a hydrogen donor or a mixture of dehydrogenated hydrogen donor and hydrogen the present method provides for subjecting the fat extracting agent to dehydrogenating conditions which are optimum for dehydrogenation without substantial degradation of the extracting agent.

In contrast to the off-gas from the catalytic cracking of gas oil which contains about 35 percent by volume of hydrogen (Table I) the make-gas of reforming unit treating Mid-Continent naphtha having a boiling range of about 160 to about 360° F. to produce C₅₊ reformate having an octane rating (Research+3 ml. TEL) of 100 has a hydrogen concentration of about 73 percent by volume as is shown in Table II. On the other hand, the make-gas from a reforming unit treating a Mid-Eastern naphtha having a boiling range of about 160° to about 360° F. to produce C₅₊ reformate having an octane rating (Research+3 ml. TEL) of 100 has a hydrogen concentration of about 61 percent by volume as is shown in Table III.

Total	100.0
Hydrogen sulfide, p.p.m.	20

In many refineries the off-gas of the naphtha pretreater is contacted with the raw naphtha to remove C₄ and heavier hydrocarbons from the pretreater gas while removing water and oxygen from the raw naphtha. Hence, the concentrations of C₄ and heavier concentrations are low enough to be disregarded. In most refineries the naphtha pretreater gas from which the hydrogen is to be recovered has the following composition (Table IV):

TABLE IV

Component:	Mol percent
Hydrogen	65.0
C ₁	20.0
C ₂	11.0
C ₃	3.7
C ₄₊	about 0.2
Hydrogen sulfide	0.1

However, it is conventional because of local anti-pollution laws to remove the hydrogen sulfide from this gas. The hydrogen sulfide content is generally reduced below 100 p.p.m.

The off-gas from a hydrodecontaminating unit for the treatment of domestic fuel oil, kerosine, jet fuel and the like has the average composition set forth in Table V.

TABLE V

Component:	Mol percent
Hydrogen	50.0
C ₁	31.0
C ₂	14.0
C ₃	4.5
C ₄	0.5
Hydrogen sulfide, p.p.m.	<100

In general, the aforescribed off-gases will be treated to reduce the sulfur content to at least 10,000 p.p.m. by volume when using a sulf-active hydrogenating catalyst and to at least 400 p.p.m. by volume when using a platinum-group metal hydrogenating catalyst. Suitable extracting agents are pure single or multi-ring aromatic hydrocarbons, pure single or multi-ring hydrocarbons having one or more saturated, i.e., alkyl side-chains, e.g., benzene, toluene, xylenes, trimethyl benzenes, ethyl benzene, diethyl benzene, ethyl-methyl benzene, naphthalene, methyl naphthalene, anthracene, methyl anthracene, phenanthrene, methyl phenanthrene, mixtures of the foregoing, aromatic petroleum fractions such as "synthetic tower" bottoms obtained in the catalytic cracking of gas oil, mixtures of aromatic hydrocarbons recovered from the extract obtained by extraction aromatic hydrocarbon-containing naphtha, kerosine "synthetic tower" bottoms, and, in general, any aromatic hydrocarbon mixture with a selective solvent such as sulfur dioxide, alkylene glycols, e.g., diethylene glycol, triethylene glycol, "Chlorex" and others. In general, the hydrogen extracting agent comprises aromatic hydrocarbon substantially devoid of hydrogenatable material not readily dehydrogenatable at extracting agent regeneration conditions without the production of unsaturated hydrocarbons. Suitable hydrogenation catalysts are hydrogenation catalysts having a hydrogenation component selected from the group consisting of the metals having atomic numbers 44 to 96 inclusive and 76 to 78 inclusive on refractory oxide base comprising alumina, silica-alumina, silica-zirconia. The

hydrogenation catalyst can be selected on the basis of the catalyst poisons present in the gas from which hydrogen is to be recovered. Thus, when the hydrogen-containing gas contains hydrogen sulfide it is preferred to use a catalyst which is not seriously inactivated by sulfur, e.g., having a hydrogenation component such as nickel-tungsten sulfide, tungsten disulfide, nickel-molybdenum sulfide. On the other hand, when the sulfur content of the hydrogen-containing gas to be treated does not exceed 30 p.p.m. (parts per million) by weight of the acceptor platinum-group metal hydrogenating catalysts such as a catalyst comprising about 0.30 to about 1.00 percent by weight of platinum, palladium, osmium, iridium on alumina base can be used. However, when desirable or necessary or convenient, the gas containing the hydrogen sulfide can be contacted with an aqueous solution of alkanolamine such as diethanolamine or other treating agent for removal of the hydrogen sulfide to provide a hydrogen-containing gas containing not more than 10 p.p.m. of sulfur by weight based on the treating agent and hydrogenating catalyst having as the hydrogenating component platinum-group metal used to recover hydrogen from the so-treated hydrogen-containing gas.

Hydrogenating conditions are as set forth in Table VI.

TABLE VI

Operating Conditions	Broad	Preferred

¹ v._h—volume of treating agent in barrels; v._c—volume of hydrogenating catalyst (barrel).

Suitable dehydrogenating catalysts are the oxides and sulfides of the metals in the left column of Group VI of the Periodic Arrangement of the Elements and particularly chromium oxide, molybdenum, and mixtures of the oxides of chromium and molybdenum. The aforesaid oxides and sulfides are used on a base or support comprising at least one refractory oxide such as alumina, silicazirconia, silica-alumina. One well known dehydrogenating catalyst comprises about 18 percent by weight chromium oxide and the balance alumina. Other suitable dehydrogenating catalysts are catalysts comprising platinum-group metal on refractory oxide support. Thus, for example, a dehydrogenating catalyst comprising about 0.35 to about 0.6 percent of platinum or alumina support is suitable. However, the preferred dehydrogenating catalyst comprises about 0.35 to about 0.6 percent by weight of platinum and not more than about 0.7 percent by weight of chlorine on alumina.

Dehydrogenating conditions are set forth in Table VII.

fea, FEA=Fat Extracting Agent.

For the recovery of hydrogen from dilute hydrogen-containing gas such as the off-gas from catalytic cracking of gas oil, naphtha pretreater off-gas, off-gas from middle distillate hydrodecontamination and similar refinery off-gases containing at least 20 percent by volume of hydrogen the dilute refinery gas is contacted with the extracting agent in a lean extracting agent-to-hydrogen mol ratio in the range of 0.20 to 5.

Illustrative of the flow of liquids and gases in the present method of recovery hydrogen of at least 90 per-

cent purity from refinery gas containing at least 20 percent of hydrogen are the flow sheets of FIGURES 1 and 2.

The flow sheet FIGURE 1 illustrates the use of two hydrogen extractors or reactors and one fat extracting agent regenerator or reactor. The hydrogen extractors or reactors are used alternately. That is to say, while one is on-stream the other is off-stream and the catalyst is regenerated usually by combustion of the coke deposited on the catalyst during the on-stream period of the cycle in any inert gas containing free oxygen. The deposition of coke in the fat extracting agent regenerator or reactor is minimal since temperature and liquid hourly space velocity are correlated to minimize hydro-cracking and dealkylation of alkyl-substituted extracting agent. It is to be noted that regeneration of the fat extracting agent FEA is an endothermic reaction which under adiabatic reaction conditions results in a temperature drop in the reactor. Since dealkylation of alkyl-substituted acceptors occurs at temperatures below that at which dehydrogenation of the hydrogenated extracting agent occurs it is desirable, and in fact preferred, to separate the regenerated or lean extracting agent from the dehydrogenating catalyst substantially as soon as the temperature of the reactant reaches that at which the dehydrogenation reaction ceases. This is most readily accomplished by contacting the fat extracting agent with the dehydrogenating catalyst at a catalyst-to-oil ratio in the range of about 0.2 to 0.5 tons of catalyst per 1000 barrels of fat extracting agent per day, i.e., at a liquid hourly space velocity (v._{fea}/hr./v._c) in the range of about 10 to about 25 when using a dehydrogenating catalyst comprising about 0.35 to about 0.6 percent by weight of platinum and not more than 0.7 percent of chlorine and/or fluorine on alumina support.

As illustrated in FIGURE 1 at start-up a lean extracting agent such as the hydrocarbons recovered from the extraction of kerosine with sulfur dioxide or the synthetic tower bottoms recovered from the product of the catalytic cracking of gas oil, or in general a hydrogenatable aromatic hydrocarbon comprising at least 60 volume percent including 100 volume percent, of aromatic hydrocarbon and substantially devoid of other hydrogenatable material is drawn from a source not shown through pipe 1 under control of valve 2. After start-up only make-up quantities of fresh extracting agent are drawn through valve 2. The extracting agent (lean) flows through pipe 1 to the suction side of pump 3. Pump 3 discharges the lean extracting agent (LEA) into pipe 4 at a pressure in excess of that in the on-stream extractor or reactor 15 or 16 by the amount of pressure drop between pump 3 and the on-stream extractor or reactor. The lean extracting agent flows through pipe 4 to indirect heat exchanger 5 where the lean extracting agent is in heat transfer relation with the effluent of the on-stream extractor or reactor flowing from effluent manifold 26. From heat exchanger 5 the lean extracting agent flows through pipe 6 to coil 7 in heater or furnace 8. In furnace 8 the lean extracting agent is heated to a temperature to provide a hydrogenation temperature at the vapor inlet of the on-stream extractor or reactor. (At this point for simplicity of description it will be assumed that extractor reactor 15 is on-stream, that extractor or reactor 16 is off-stream, and that the catalyst in reactor 16 is being regenerated in combustion-supporting gas. It will also be assumed that the hydrogenating catalyst is nickel-tungsten sulfide and that the refinery off-gas containing at least 20 percent by volume of hydrogen contains not more than about 10,000 p.p.m. by volume of sulfur as hydrogen sulfide.)

Contemporaneously with the flow of lean extracting agent through reactor 15 refinery off-gas containing at least 20 percent by volume of hydrogen and not more than 10,000 p.p.m. by volume of sulfur as hydrogen sulfide flows from a source not shown through conduit

17 to compressor 18. Compressor 18 discharges the refinery off-gas into conduit 19 at a pressure in excess of that in reactor 15 by the pressure drop between compressor 18 and reactor 15. The compressed refinery off-gas flows through conduit 19 to coil 20 in furnace or heater 21. In heater 21 the refinery off-gas is heated to a temperature such that when mixed with the heated lean extracting agent in inlet manifold 10 the mixture will have a hydrogenating temperature. The heated lean extracting agent and heated refinery off-gas flow respectively through pipe 9 and conduit 22 to inlet manifold 10.

The lean extracting agent-to-hydrogen mol ratio depends on the extracting agent employed. For example, if naphthalene is used, one mol can bind as many as five mols of hydrogen when completely hydrogenated in accordance with the following equation:

Thus, the lean extracting agent-to-hydrogen mol ratio is 0.20 (1/5) for complete hydrogenation of the naphthalene. For partial hydrogenation (to tetralin), the lean extracting agent-to-hydrogen mol ratio is 0.50 (1/2). In the case of benzene, one mol can react with a total of three mols of hydrogen when completely hydrogenated in accordance with the following equation:

The lean extracting agent-to-hydrogen mol ratio for benzene is 0.33 (1/3). However, to ensure maximum recovery of hydrogen from the dilute (with respect to hydrogen) refinery off-gas an excess of hydrogenatable aromatic hydrocarbon above that which theoretically can be hydrogenated by the hydrogen of the dilute refinery off-gas is generally used. Accordingly, it is preferred to employ lean extracting agent-to-hydrogen mol ratios as much as five. This excess of lean extracting agent not only ensures maximum extraction of the hydrogen from the dilute refinery off-gas but also more ready control of the temperature of the endothermic reaction.

Returning to a description of FIGURE 1; the heated lean extracting agent and dilute refinery off-gas are mixed in inlet manifold 10 in the proportion of at least 0.20 mol of hydrogenatable aromatic hydrocarbon per mol of hydrogen in the dilute refinery off-gas to provide an extraction mixture. The extraction mixture at hydrogenation temperature flows through inlet manifold 10 to manifold branch 11 (valve 14 closed; valve 12 open). The extraction mixture flows downwardly in reactor 15 in contact with hydrogenation catalyst. The fat extracting agent, i.e., at least partially hydrogenated aromatic hydrocarbon, and denuded refinery off-gas, designated extractor effluent, flow from reactor 15 through manifold branch 23 (valve 24 open; valve 28 closed) to outlet manifold 26. The extractor effluent flows through outlet manifold 26 to indirect heat exchanger 5 to conduit 30 and cooler 31. In cooler 31 the extractor effluent is cooled to a temperature at which the fat extracting agent is liquid at the existing pressure. The cooled extractor effluent flows from cooled 31 through conduit 32 to liquid-gas separator 33. In liquid-gas separator 33 the uncondensed denuded refinery off-gas separates from the condensed fat extracting agent. The uncondensed denuded refinery off-gas comprising C₁ to C₅ hydrocarbons flows from separator 33 through conduit 34 to hydrocarbon recovery, processing, the refinery fuel main, or the refinery flare.

The condensed fat extracting agent flows from separator 33 through pipe 35 to the suction side of pump 36. The fat extracting agent is discharged into pipe 37 by pump 36 at a pressure greater than the pressure in reactor 25 by the pressure drop between pump 36 and reactor 25.

The fat extracting agent flows through pipe 37 to indirect heat exchanger 38. In indirect heat exchanger 38

the fat extracting agent is in heat transfer relation with the effluent of reactor 25 comprising hydrogen and lean extracting agent flowing from reactor 25 through conduit 43. From indirect heat exchanger 38 the fat extracting agent flows through conduit 39 to coil 40 in furnace or heater 41. At a point in conduit 39, intermediate to indirect heat exchanger 38 and to furnace 41, 90 percent or better hydrogen flowing from compressor 51 through conduit 52 is mixed with the fat extracting agent in the mol ratio of about 1 to about 20, preferably about 3 to 10 mols of hydrogen per mol of hydrogenated aromatic hydrocarbon to provide a recovery charge.

The recovery charge is heated in furnace 41 to a dehydrogenating temperature to provide a vapor inlet temperature at reactor 25 in the range of about 800° to about 1050° F. The heated recovery charge flows from heater 41 through conduit 42 to reactor 25. The recovery charge flows downwardly through reactor 25. The extracting agent regenerator effluent comprising hydrogen and lean extracting agent flows from reactor 25 through conduit 43, indirect heat exchange 38 and conduit 44 to cooler 45. In cooler 45 the extracting agent regenerator effluent is cooled to a temperature at which the extracting agent is condensed at the existing pressure. The uncondensed hydrogen and minor concentration of hydrocarbons together with the condensed lean extracting agent flow from cooler 45 through conduit 46 to liquid-gas separator 47.

30 In liquid-gas separator 47 the uncondensed recovered hydrogen and hydrocarbons boiling below the boiling point of the extracting agent separate from the condensed lean extracting agent and flow therefrom, as a gaseous stream containing at least 90 percent by volume of hydrogen balance, to make 100 percent by volume, hydrocarbons boiling below the boiling point of the extracting agent, through conduit 48 to hydroporesses. A portion of the at least 90 percent pure hydrogen is diverted from conduit 48 under control of valve 50 to conduit 49 and the suction side of compressor 51. The quantity of 90 percent pure hydrogen so diverted is sufficient to provide the aforesaid 1 to 20, preferably 3 to 10 mols of hydrogen per mol of hydrogenated aromatic hydrocarbon in the recovery charge. Compressor 51 recompresses the 90 percent pure hydrogen to a pressure in excess of that in conduit 39. The recompressed 90 percent pure hydrogen flows from compressor 51 through conduit 52 to conduit 39.

The condensed lean extracting agent (LEA) separated 50 in liquid-gas separator 47 from the uncondensed at least 90 percent pure hydrogen, flows from separator 47 through pipe 53 and 1 to the suction side of pump 3 (valve 54 open; valve 2 closed except to admit make-up extracting agent to pipe 1). The lean extracting agent 55 is then recycled to the hydrogenating-reactor or extractor 15 or 16 which is on-stream to extract hydrogen from further quantities of refinery off-gas containing at least 20 percent by volume of hydrogen. Those skilled in the art will recognize that for simplicity the piping required for regeneration of coked catalyst has been omitted since regeneration of catalyst deactivated with coke is too well known to require description. Briefly, the catalyst in the off-stream extractor, presently assumed for descriptive purposes to be reactor 16, is regenerated by isolating 60 the reactor or extractor from the extracting agent and refinery off-gas and from extractor effluent manifold. The extractor or reactor is plugged with inert gas such as flue gas, steam, nitrogen. The purged reactor is then pressured with flue gas and the flue gas heated and encirculated until 65 the temperature in the catalyst bed is at a burning temperature. Free oxygen, e.g., air is then admixed which the circulating inert gas and the coke burned from the catalyst. When the burning front reaches the bottom of the catalyst bed and free oxygen is detected in the effluent gas the 70 supply of air is cut-off and the reactor purged until the 75

oxygen content of the effluent gases does not exceed 1 mol-percent. The reactor or extractor is then pressured with refinery off-gas to be extracted and the flow of heated lead extracting agent and refinery off-gas to be extracted diverted from the on-steam extractor or reactor to the off-steam extractor in which the catalyst has been regenerated.

FIGURE 2 is a flow sheet likewise illustrating the use of three reactors for extracting hydrogen from dilute refinery gas streams and recovering the extracted hydrogen. However, whereas in the embodiment illustrated in FIGURE 1 one reactor is used only for the recovery of extracted hydrogen while the other two reactors are used alternatively for extracting hydrogen in the embodiment illustrated in FIGURE 2 all of the reactors are charged with a catalyst having not only hydrogenating capabilities but also having dehydrogenating capabilities.

Catalysts having hydrogenating and dehydrogenating capabilities suitable for use in the present method are for example, a mixture of oxides of cobalt and molybdenum on alumina support; platinum-group metal on refractory oxide support, such as alumina, silica-alumina, and the like; and catalysts comprising a mixture of at least 18 percent by weight of at least one oxide of chromium, molybdenum, and vanadium, and at least one refractory oxide such as alumina, silica, zirconia.

The embodiment illustrated in FIGURE 2 has particular advantages when recovering hydrogen from dilute refinery gas containing more than 30 p.p.m. of sulfur based upon the weight of the hydrogenatable aromatic hydrocarbons used as, for example, when recovering hydrogen from the hydrogen-containing off-gases from a hydrodesulfurizing unit treating middle distillate fuels such as kerosine, domestic fuel oil, jet fuels and the like. For example, the hydrogen-containing gas from a hydrodesulfurization unit hydrotreating a middle distillate e.g., domestic fuel oil has the following average composition:

TABLE VIII

Dilute off-gas component:	Mol percent
Hydrogen	43.3
C ₁	36.6
C ₂	15.2
C ₃	4.1
C ₄₊	0.8
Hydrogen sulfide, p.p.m.*	500
Ammonia, p.p.m.*	200

* P.p.m.—parts per million by volume on gas.

While a dilute off-gas containing such a concentration of sulfur and ammonia must be pretreated to reduce the sulfur concentration to not more than 30 p.p.m. by weight based on the extracting agent (15 to 400 p.p.m. by volume based on the gas for treating agent-to-hydrogen mol ratios in the range of 0.20 to 5) and the ammonia concentration to not more than 5 p.p.m. by weight based on the said extracting agent (5 to 150 p.p.m. by volume based on the gas for hydrogenatable aromatic-to-hydrogen mol ratios in the range of 0.20 to 5) when platinum-group metal catalyst having hydrogenating and dehydrogenating capabilities is employed for extracting hydrogen (from dilute off-gas) and recovering hydrogen (from lean extracting agent), in contrast when using sulfur and nitrogen-insensitive catalyst having hydrogenating and dehydrogenating capabilities such as a mixture of oxides of chromium and aluminum, or of oxides of chromium, molybdenum, and aluminum, or of oxides of cobalt, molybdenum, and aluminum, the concentrations of sulfur and ammonia in the dilute off-gas can be as high as 10,000 p.p.m. by volume and 1500 p.p.m. by volume respectively, i.e., 750 p.p.m. and 50 p.p.m. by weight based on the lean extracting agent using a mol ratio in the range of 0.20 to 5 mols of said aromatic hydrocarbon per mol of hydrogen. Dilute off-gas such as the aforesaid dilute off-gas from a hydrodesulfurization unit treating middle

distillate fuel oil as characterized in Table VIII is illustrative of dilute off-gas treated in accordance with the flow-sheet of FIGURE 2.

Reactors 114, 160, and 141 are charged with sulfur and nitrogen-insensitive catalyst having both hydrogenating and dehydrogenating capabilities. Lean extracting agent, for example, synthetic crude tower bottoms from a catalytic cracking unit having the average composition set forth in Table IX is drawn from a source not shown through pipe 101 under control of valve 102 by pump 103.

Aromatics (principally polyalkylbenzenes) 60–61.8 vol. percent.

The lean extracting agent is discharged by pump 103 into pipe 104 at a pressure greater than that in the reactor of reactors 114, 160, and 141 on-stream by at least the pressure drop between pump 103 and the on-stream reactor. The lean extracting agent flows through pipe 104 to coil 105 in furnace or heater 106. In heater 106 the lean extracting agent is heated to a temperature such that when mixed with dilute off-gas in the ratio of about 0.20 to about 5 mols of hydrogenatable aromatic per mol of hydrogen in the dilute off-gas the extraction mixture so-formed has a hydrogenating temperature at the vapor inlet of the on-stream extractor or hydrogenating reactor. (For simplicity it will be assumed that the following cycle having the indicated phases is employed.)

TABLE X

40		R ₁ (114)	R ₂ (160)	R ₃ (141)
	First Phase	Extracting Hydrogen.	Idle	Regeneration of Extracting Agent.
45	Second Phase	Regeneration of Catalyst.	Regeneration of Extracting Agent.	Extraction of Hydrogen to about 10% coke on catalyst.
	Third Phase	Regeneration of extracting agent.	Extraction to about 10% coke on catalyst.	Regeneration of catalyst.
50	Fourth Phase	Extraction to about 10% coke on catalyst.	Regeneration of catalyst.	Regeneration of extracting agent.
	Fifth Phase	Regeneration of catalyst.	Regeneration of extracting agent.	Extraction to about 10% coke on catalyst.
55	Sixth Phase	Regeneration of extracting agent.	Extraction to about 10% coke on catalyst.	Regeneration of catalyst.

The heated lean extracting agent flows from furnace 106 through conduit 107 to inlet manifold 108 and manifold branch 112 (valve 113 open; valves 159 and 140 closed). At a point in conduit 107 intermediate to inlet manifold 108 and heater 106 the dilute off-gas from which hydrogen is to be recovered is mixed with the lean extracting agent in a mol ratio in the range of 0.20 to 5 mols of hydrogenatable aromatic per mol of hydrogen. The dilute off-gas flows from a source not shown through conduit 110 to the suction side of compressor 109. Compressor 109 compresses the off-gas to a pressure at least equal to that in conduit 107 and discharges the off-gas into conduit 111 through which the off-gas flows to conduit 107 and admixture with the lean extracting agent. (Those skilled in the art will appreciate that when the off-gas is available contiguous to conduit 107 recom-

pression is unnecessary and compressor 109 can be bypassed.)

The extractor mixture comprising off-gas and lean extracting agent in proportions to provide 0.20 to 5 mols of hydrogenatable aromatic per mol of hydrogen in the off-gas flows through conduit 107 to extractor inlet manifold 108. From extractor inlet manifold 108 in the first phase of the cycle the extractor mixture flows through manifold branch 112 (valve 113 open; valves 159 and 140 closed; valves 166, and 157 closed) to extractor reactor 114. The extractor mixture flows downwardly in extractor 114 in contact with particle-form solid hydrogenating catalyst in this description sulfur- and nitrogen-insensitive hydrogenating catalyst. The extractor effluent comprising fat extracting agent and extracted off-gas flows from extractor 114 to manifold branch 115. (Valve 116 open; valves 168, 162, 164, and 143 closed.) The extractor effluent flows through manifold branch 115 to extractor effluent manifold 117. The extractor effluent flows through extractor effluent manifold 117 to indirect heat exchanger 118 where the extractor effluent is in heat transfer relation with lean extracting agent flowing from indirect heat exchanger 120 through conduit 154. From indirect heat exchanger 118 the extractor effluent flows through conduit 119 to indirect heat exchanger 120 where the extractor effluent is in heat transfer relation with lean extracting agent flowing from liquid-gas separator 151 through pipe 153. From indirect heat exchanger 120 the extractor effluent flows through conduit 121 to cooler 122. In cooler 122 the extractor effluent is cooled to a temperature at which the fat extracting agent is condensed at the existing pressure. (Fat extracting agent as used hereinbefore, here, and hereinafter designates extracting agent in which the hydrogenatable aromatic has been in contact with hydrogen-containing gas in the presence of hydrogenating catalyst under hydrogenating conditions of temperature, pressure, and liquid hourly space velocity regardless of the degree of completeness of the hydrogenation of said hydrogenatable aromatic hydrocarbon. Thus, for extracting agents containing hydrogenatable aromatic hydrocarbons such as benzene and alkylbenzenes it is immaterial whether all of the molecules each have accepted six atoms of hydrogen or only one atom of hydrogen or that a portion of the molecules of the aromatic each have accepted one atom of hydrogen and the balance none of a portion of the molecules of the aromatic each have accepted one to six atoms of hydrogen and the balance none.) The cooled extractor effluent comprising extracted off-gas and fat extracting agent flows from cooler 122 through conduit 123 to gas-liquid separator 124. In gas-liquid separator 124 the extracted off-gas separates from condensed fat extracting agent. The extracted off-gas, designated waste gas, flows from separator 124 through conduit 125 to means for recovery of hydrocarbons, isomerization of hydrocarbons, hydrocarbon conversion as of methane to acetylene, the refinery fuel main, the refinery flare or other means of treating a hydrocarbon stream of this composition.

The condensed fat extracting agent flows from separator 124 through pipe 126 to indirect heat exchanger 127 where the fat extracting agent is in heat transfer relation with extracting agent regenerator effluent flowing from regenerator outlet manifold 146, indirect heat exchanger 129, conduit 147 to indirect heat exchanger 127. From indirect heat exchanger 127 the fat extracting agent flows through pipe 128 to indirect heat exchanger 129 where the fat extracting agent is in heat transfer relation with the regenerator effluent flowing from fat extracting agent regenerator manifold 146. From indirect heat exchanger 129 the fat extracting agent flows through pipe 130 to the suction side of pump 131. Pump 131 discharges the fat extracting agent into pipe 132 through which the fat extracting agent flows to coil 133 in furnace or heater 134.

In furnace 134 the fat extracting agent is heated to a temperature such that, when mixed with hydrogen in regenerator inlet manifold 136 to provide a regeneration feed comprising about 1 to about 20 mols of hydrogen of at least 90 percent purity per mol of hydrogenated aromatic hydrocarbon, a vapor inlet dehydrogenation temperature of about 800° to about 1050° F. at the regenerator-reactor inlet (141) is provided. From heater 134 the heated fat extracting agent (FEA) flows through pipe 135 to regenerator inlet manifold 136. In regenerator inlet manifold 136 the fat extracting agent is mixed with hydrogen of 90 percent purity flowing either from a source not shown through conduits 171 and 169 under control of valve 172 or after start-up from liquid-gas separator 151, and conduits 152 and 169 under control of valve 170. (When recovered hydrogen or extraneous hydrogen is not available at a pressure at least equal to that in regenerator manifold 136 the extraneous hydrogen and the recovered hydrogen is compressed to the necessary pressure for introduction into regenerator manifold 136.)

From regenerator inlet manifold 136 the regenerator charge mixture comprising fat extracting agent and hydrogen in the ratio set forth hereinbefore flows through manifold branch 137 (valve 138 open; valves 157 and 166 closed; valve 140 closed) and manifold branch 139 to regenerator 141. The regenerator charge mixture flows downwardly in regenerator 141 in contact with dehydrogenating catalyst described hereinbefore. The regenerator effluent comprising recycle hydrogen, i.e., hydrogen admixed in regenerator manifold 136, make-hydrogen, i.e., hydrogen removed from the fat extracting agent and lean extracting agent flows from regenerator 141 through manifold branch 144 (valve 145 open; valves 143, 164, and 168 closed) to regenerator manifold 146. From regenerator manifold 146 the regenerator effluent flows to indirect heat exchanger 129, conduit 147, indirect heat exchanger 127 and conduit 148 to cooler 149.

In cooler 149 the regenerator effluent comprising hydrogen and lean extracting agent is cooled to a temperature at which the lean extracting agent is liquid. The condensed lean extracting agent and uncondensed hydrogen flow from cooler 149 through conduit 150 to liquid-gas separator 151.

In liquid-gas separator 151 hydrogen of at least 90 percent purity separates from lean extracting agent. The hydrogen of at least 90 percent purity flows from separator 151 through conduit 152 to use in other hydro processes. A portion to provide about 1 to about 20 mols of hydrogen per mol of hydrogenatable aromatic hydrocarbon in regenerator manifold 136 as described hereinbefore is diverted through conduit 169 under control of valve 170 (valve 172 closed).

The condensed lean extracting agent flows from separator 151 through pipe 153 to indirect heat exchanger 120, pipe 154, indirect heat exchanger 118 and pipe 155 to pipe 101 for use as extracting agent for the extraction of hydrogen from further amounts of dilute refinery off-gas.

As set forth in Table X supra in the first phase of a cycle reactor 114 is in the extraction operation, reactor 141 is in the regeneration of the extracting agent, and reactor 160 is idle. When the activity of the catalyst in reactor 114 is reduced to an industrially appreciable extent as indicated by a decrease in the difference in temperature between the temperature of the extractor effluent and the vapor inlet of the extractor, the extractor is taken off-stream and the catalyst regenerated. Regenerator 141 is then preferably taken off regenerating of the extracting agent and used for extracting hydrogen from the dilute refinery off-gas. Reactor 160 which in the first phase of the cycle is idle is then placed in the fat extracting agent regenerating operation. Operation in the second phase of the cycle then proceeds until the catalyst in reactor 141 has been contaminated by the deposition of an amount of coke equal to about 10 percent by weight

of the catalyst therein as determined, for example, by the decrease in the difference between the temperature of the extractor effluent and the vapor inlet temperature. (Hydrogenation being an exothermic reaction the temperature of the extractor effluent is higher than the vapor inlet temperature. The more vigorous the hydrogenation, i.e., the more active the hydrogenation, the greater the temperature rise.) Reactor 141 is then taken off-stream and the catalyst therein regenerated while reactor 160 (extracting agent regeneration in the second phase) is put on-stream as an extractor until about 10 percent by weight of coke is deposited thereon and reactor 114 (catalyst now regenerated) is put on-stream for regeneration of the extracting agent in the third phase of the cycle. In the fourth phase of the cycle the catalyst in reactor 160 (extraction stage in the third phase) is regenerated, reactor 141 (regeneration of catalyst in the third phase) is used for regeneration of the extracting agent, and reactor 114 previously used in the regeneration of extracting agent is used for extracting hydrogen from dilute refinery off-gas until the amount of coke deposited on the catalyst amounts to about 10 percent by weight thereof.

In the fifth phase of the cycle the catalyst in reactor 114 is regenerated, reactor 141 is used as a hydrogen extractor, and reactor 160 is used to regenerate the fat extracting agent. In the sixth phase of the first cycle reactor 114 is used for the regeneration of the fat extracting agent, reactor 160 is used as an extractor of hydrogen from dilute refinery off-gas and the catalyst in reactor 141 is regenerated. This ends the first cycle.

Those skilled in the art will recognize that there is nothing immutable in the sequence in which the reactors appear in any cycle. That is to say, in the first phase of the first cycle reactor 141 can be used as an extractor, reactor 160 used for regeneration of the extracting agent and reactor 114 can be idle. The other possible combination can also be used in the first phase. However, it is preferred after the first phase to use the reactor in which the catalyst is fresh or regenerated for regeneration of the extracting agent and to use the catalyst which in the previous phase was used for regeneration of the extracting agent for the extraction of hydrogen from refinery gas streams dilute with respect to hydrogen.

I claim:

1. A method of recovering hydrogen from refinery gas dilute with respect to hydrogen which comprises in a gas extractor contacting refinery gas comprising at least about 20 percent by volume of hydrogen and an extracting agent having as its sole hydrogenatable material at least one aromatic hydrocarbon with hydrogenating catalyst at hydrogenating conditions of temperature, pressure, and liquid hourly space velocity, obtaining extractor effluent comprising fat extracting agent and extracted refinery gas, cooling said extractor effluent to a temperature at which said fat extracting agent is condensed at the existing pressure, separating said cooled extractor effluent into waste gas comprising refinery gas having reduced hydrogen content and fat extracting agent, in an extracting agent regenerator contacting only said separated fat extracting agent in admixture with hydrogen of at least 90 percent purity with dehydrogenating catalyst at dehydrogenating conditions of temperature, pressure, and liquid hourly space velocity whilst maintaining a concentration of at least 90 percent of hydrogen in the fraction of reaction vapors boiling below the boiling point of said lean extracting agent, separating regenerator vapor from dehydrogenating catalyst after said fat extracting agent has contacted not more than 0.2 to 0.5 ton of said platinum-group metal dehydrogenating catalyst per 1000 barrels of extracting agent regenerated per day, said separated regenerator vapors comprising said admixed hydrogen, hydrogen produced in said regenerator, and lean extracting agent, cooling said separated regenerator vapors to a temperature at which said lean extracting agent is condensed at the existing pressure, separating said cooled regenerator vapors into a gaseous fraction containing at least 90 percent by volume of hydrogen and liquid lean extracting agent, recycling a portion of said gaseous fraction to the regenerator to supply the admixed hydrogen of at least 90 percent purity, recovering the balance of said gaseous fraction as hydrogen of at least 90 percent purity, and recycling at least a portion of said lean extracting agent to said extractor.

condensed lean extracting agent, recycling a portion of said gaseous fraction to said extracting agent regenerator and recovering the balance of said gaseous fraction as hydrogen of at least 90 percent purity, and recycling at least a portion of said condensed lean extracting agent to the aforesaid gas extractor.

2. The method of claim 1 wherein the hydrogenating catalyst and the dehydrogenating catalyst are of substantially the same composition.

3. The method set forth in claim 1 wherein the hydrogenating catalyst and the dehydrogenating catalyst are of substantially different composition.

4. The method set forth in claim 1 wherein the hydrogenating component of the hydrogenating catalyst is substantially the same as the dehydrogenating component of the dehydrogenating catalyst.

5. The method set forth in claim 1 wherein the hydrogenating component of the hydrogenating catalyst is different to the dehydrogenating component of the dehydrogenating catalyst.

6. The method set forth in claim 1 wherein three reactors are charged with substantially the same quantity of particle-form solid catalytic material having hydrogenating and dehydrogenating capabilities, wherein a cyclic manner catalyst having a coke deposit of about 10 percent by weight based on the catalyst is regenerated, then used for extracting hydrogen from refinery gas dilute with respect to hydrogen.

7. The method set forth in claim 6 wherein the particle-form solid catalytic material is sulfur and nitrogen insensitive.

8. The method set forth in claim 6 wherein the particle-form solid catalytic material is platinum-group metal and the refinery gas to be extracted contains not more than 400 p.p.m. volume of hydrogen sulfide.

9. A method of recovering hydrogen from refinery gas dilute with respect to hydrogen which comprises in a gas extractor contacting refinery gas comprising at least about 20 percent by volume of hydrogen and an extracting agent having as its sole hydrogenatable material at least one aromatic hydrocarbon with hydrogenating catalyst at hydrogenating conditions of temperature, pressure, and liquid hourly space velocity, obtaining extractor effluent comprising fat extracting agent and extracted refinery gas, cooling said extractor effluent to a temperature at which said fat extracting agent is condensed at the existing pressure, separating said cooled extractor effluent into waste gas comprising refinery gas having reduced hydrogen content and fat extracting agent, in an extracting agent regenerator contacting only said separated fat extracting agent admixed with hydrogen of at least 90 percent purity with platinum-group metal dehydrogenating catalyst at dehydrogenating conditions of temperature, pressure and liquid hourly space velocity whilst

55 maintaining a concentration of at least 90 percent of hydrogen in the fraction of reaction vapors boiling below the boiling point of said lean extracting agent, separating regenerator vapor from dehydrogenating catalyst after said fat extracting agent has contacted not more than 0.2 to 0.5 ton of said platinum-group metal dehydrogenating catalyst per 1000 barrels of extracting agent regenerated per day, said separated regenerator vapors comprising said admixed hydrogen, hydrogen produced in said regenerator, and lean extracting agent, cooling said separated regenerator vapors to a temperature at which said lean extracting agent is condensed at the existing pressure, separating said cooled regenerator vapors into a gaseous fraction containing at least 90 percent by volume of hydrogen and liquid lean extracting agent, recycling a portion of said gaseous fraction to the regenerator to supply the admixed hydrogen of at least 90 percent purity, recovering the balance of said gaseous fraction as hydrogen of at least 90 percent purity, and recycling at least a portion of said lean extracting agent to said extractor.

10. The method set forth in claim 9 wherein the hydrogenating catalyst is selected from the group consisting of mixture of oxides of cobalt and molybdenum, nickel-tungsten, sulfide, tungsten disulfide, and nickel-molybdenum sulfide.

11. The method set forth in claim 9 wherein the dehydrogenating catalyst comprises about 0.35 to about 0.6 percent by weight of platinum on alumina support.

12. The method set forth in claim 9 wherein the refinery gas is treated to reduce the sulfur and nitrogen content thereof to not more than 400 p.p.m. by volume and 150 p.p.m. by volume respectively.

13. The method set forth in claim 9 wherein the refinery gas is treated to reduce the sulfur and nitrogen content thereof to not more than 400 p.p.m. by volume and 150 p.p.m. by volume respectively, wherein the hydrogenating catalyst comprises about 0.35 to about 0.6 percent by weight of platinum on alumina and wherein the

platinum group metal dehydrogenating catalyst comprises about 0.35 to about 0.6 percent by weight of platinum on alumina support.

14. The method set forth in claim 9 wherein the refinery gas contains not more than 10,000 p.p.m. by volume of sulfur and not more than 1,500 p.p.m. by volume of nitrogen, wherein the hydrogenating catalyst is nickel-tungsten sulfide, and wherein the dehydrogenating catalyst comprises about 0.35 to about 0.6 percent by weight of platinum on alumina support.
